(57) **CLAIM**

The ornamental design for a window, as shown and described.

DESCRIPTION

The patent or application file contains at least one drawing executed in color. Copies of this patent or patent application publication with color drawing(s) will be provided by the Office upon request and payment of the necessary fee.

1. Window

1.1 : Front

1.2 : Back

1.3 : Enlarged, top, right view of the front

1.4 : Enlarged, top, left view of the front

1.5 : Enlarged, bottom, left view of the front

1.6 : Enlarged, bottom, right view of the front

1.7 : Enlarged, top, left view of the back

1.8 : Enlarged, top, right view of the back

1.9 : Enlarged, bottom, right view of the back

1.10 : Enlarged, bottom, left view of the back

Design concerns a window encompassing a casing and a casement; for the faded and grayed out parts protection is not sought; the protection is claimed for the parts in normal colors; these parts are placed in the corners (top right, top left, bottom left and bottom right) of the casing and the casement; the characteristic feature of the design is smooth, even and uniform surface at the junction of the casing and the casement profiles.

The broken lines depict the bounds of the claim. The half-tone areas outside of the broken lines depict portions of the window that form no part of the claimed design.
